UNITED STATES PATENT OFFICE.

CARL M. FELLMAN, OF ROSICLARE, ILLINOIS.

SHOE PROTECTOR.

Application filed July 24, 1925. Serial No. 45,882.

This invention relates to a shoe protector, the general object of the invention being to provide a metal covered auxiliary sole for protecting the shoe from wear when a person is engaged in an occupation or play which subjects the shoe to great wear, such as when a child uses a coaster wagon or similar device and propels himself along with his foot striking the ground.

10 This invention also consists in certain other features of construction and in the combination and arrangement of the several parts, to be hereinafter fully described, illustrated in the accompanying drawings and specifically pointed out in the appended 15 claim.

In describing my invention in detail, reference will be had to the accompanying drawings wherein like characters denote like 20 or corresponding parts throughout the several views, and in which:

Figure 1 is a view of a shoe, showing the invention in use.

Figure 2 is a top plan view of the attachment.

Figure 3 is a section on line 3—3 of Figure 2.

Figure 4 is a section on line 4—4 of Figure 2.

30 Figure 5 is a view of the metal plate.

As shown in these views, the auxiliary sole shown generally at A is composed of a strip of leather 1 which covers the sole of the shoe from the toe to the heel and a metal plate 2 which is fastened to the strip by having points 3 struck up therefrom and driven through the strip and bent over to firmly connect the plate to the strip. This plate does not extend over the instep portion of 40 the leather strip 1. Clips 4 are fastened to

the edges of the auxiliary sole by rivets 5 or the like, and straps 6 are fastened to the upstanding portions of the clips, the straps being adapted to be buckled together, as shown at 7. A strap 8 may be connected 45 with the straps which extend over the instep of the shoe, said strap extending around the heel of the shoe, as shown in Figure 1.

From the foregoing it will be seen that the 50 leather part of the auxiliary sole is protected by the metal plate against wear and that this auxiliary sole will prevent wear on the main sole when a child is using his foot to propel himself along on a coaster or other 55 device.

This device can be easily and quickly removed from the shoe and placed thereon.

It is thought from the foregoing description that the advantages and novel features 60 of my invention will be readily apparent.

I desire it to be understood that I may make changes in the construction and in the combination and arrangement of the several parts, provided that such changes fall 65 within the scope of the appended claim.

What I claim is:—

A protector for a shoe comprising an auxiliary sole formed of a strip of leather and a metal plate on the bottom of the strip, 70 said plate having points struck therefrom and driven through the strip to hold the parts together, angle shaped clips each having one portion riveted to the auxiliary sole between the leather strip and the metal 75 plate and straps connected with the clips for fastening the auxiliary sole to a shoe.

In testimony whereof I affix my signature.

CARL M. FELLMAN.
